Specification for Design.

Patented July 5, 1921.

Application filed March 15, 1920. Serial No. 366,117. Term of patent 14 years.

To all whom it may concern:

Be it known that I, JOHN H. LICKERT, a citizen of the United States, residing at Evanston, in the county of Cook and State of Illinois, have invented a new, original, and ornamental Design for a Cutlery-Cabinet, of which the following is a specification, reference being had to the accompanying drawing, forming a part thereof.

I claim:

The ornamental design for a cutlery cabinet as shown.

JOHN H. LICKERT.
